UNITED STATES PATENT OFFICE

ALBERT WICHMANN, OF GUTZKOW, GERMANY

FASTENING FOR WEARING APPAREL

Application filed September 28, 1929, Serial No. 395,850, and in Germany March 1, 1929.

The present invention relates to improvements in fastenings for wearing apparel, more particularly an improved double clip by means of which adjoining edge portions 5 of two articles of dress, more particularly washable articles and under-garments, may be joined together in a non-permanent way.

The improved fastening or double clip consists of a piece of flat metal strip, which is 10 bent into S-shape in such manner that the slightly bent outer members or limbs which extend in opposite directions, bear with resilient pressure against a middle portion connecting the two outer members. The two 15 outer members have extensions of substantial length extending beyond the middle portion and provided at their ends with thickened rounded portions. One of the outer 20 members is provided with a stamped-out tongue which is bent backwards through about 180° and is formed at its end with an eye for the reception of a band or cord by means of which the fastening or clip can be easily removed or handled.

In order to effect a connection between 25 two articles of dress or wearing apparel, by means of the improved clips, the adjoining edges of the articles to be connected are each provided with a sewn-on band of about 20 cm. width. This band should preferably be 30 provided or formed on one side with a strengthened or reinforced edge. The longitudinal stitchings of the bands are interrupted at certain distances so as to form between the bands and the articles openings or 35 pockets into which the clip may be inserted, and these openings or pockets are reinforced by cross stitching at both sides of the opening. The openings or pockets thus provided 40 at the edge of one article should correspond or register with the openings provided in the adjacent edge portion of the other article so that by inserting the double clips into the registering openings or pockets of the 45 two adjoining edges of the articles the two articles may be detachably connected.

It will be understood that the edge portions of the articles are held together by the resilient pressure exerted by the outer limbs 50 of the S-shaped double clips, the edge por-

tions of each article being gripped between the outer limb of the clip and the middle portion thereon.

In order to separate the two articles, one article is pulled out of the clips, whereupon 55 the clips may be singly removed by means of their tongues out of the other article. It will be understood that the clips may, for instance be used for attaching a skirt to a bodice, or they may also be used for connecting 60 the adjoining edges of articles of laundry in place of the usual buttons.

The drawings show by way of example one construction according to the invention.

Fig. 1 shows the improved clip in plan, 65 and

Fig. 2 is a side view corresponding to Fig. 1.

Fig. 3 shows by way of example the application of the improved fastenings, the left 70 hand portion of Fig. 3 showing the fastening applied to the top edge of an article and ready to receive the lower edge of another article, whilst the right hand portion of Fig. 3 shows two superposed edge portions 75 connected by the improved clip which lies entirely in the pockets and is therefore invisible with the exception of the end of the tongue.

Referring to Figs. 1 and 2, the improved 80 S-shaped double clip consists of a middle portion *a* and two longer oppositely extending outer portions or limbs *b* and *c* which are only slightly curved and bear with resilient pressure against the middle portion. Rounded portions join the middle portion *a* to the outer limbs *b* and *c*. The ends of the outer limbs *b* and *c* which extend beyond the inner portion *a* are formed with thickened rounded portions *d* which facilitate the insertion of 85 the clip into the corresponding pockets formed in the dress edges. As may be seen from Fig. 1, the outer ends of *b* and *c* are somewhat tapered or reduced in width, also for the purpose of facilitating insertion.

The tongue *e* is stamped out of one of the outer limbs, namely *b*, and is so bent backwards as to extend outwardly beyond the end *d* of the other limb. The end of the tongue *e* is formed into an eye or loop *f* for the re- 100

ception of a band or cord which serves as means for removing the fastening from the dress. As may be seen from Fig. 3, the adjoining edges *g* and *h* of the two articles of dress to be connected together by means of the improved fastening, are provided with sewn-on bands *i* and *k*. These bands are preferably formed with reinforced edges and are sewn on by means of interrupted longitudinal stitching and suitable cross stitchings in such a manner as to provide at certain distances pockets *l* into which the clips are inserted. The pockets of the two edge portions must, of course, correspond or register.

15 In the left hand portion of Fig. 3 a double clip is shown inserted into a pocket of the edge *g* by means of its upper limb *b*. The lower limb *c* is visible as well as the tongue *f*. The right hand portion of Fig. 3 shows a fastening inserted into corresponding pockets of adjoining edge portions so that only the eye *f* of the tongue remains visible.

20 It will be understood that in order to separate the edge portion *h* from the edge portion *g*, it is sufficient to pull the edge *h* downwards out of the clips which then remain in the edge portion *g* and may be removed from the latter by means of the eyes *f* or a cord inserted through the latter.

25 I claim:

30 1. A fastening for wearing apparel consisting of an S-shaped double spring clip having two outer slightly curved oppositely directed members connected by short rounded portions to a common middle member of shorter length, the projecting ends of the outer members being formed with thickened rounded portions on the sides adjacent to the middle member, substantially as described.

35 2. A fastening for dress apparel consisting of an S-shaped double spring clip made of a single piece of metal and composed of two oppositely directed slightly curved outer spring members connected by a shorter common inner member, the projecting ends of the outer members being tapered and formed with ball shaped end portions, substantially as described.

40 3. A fastening for dress apparel consisting of an S-shaped double spring clip having two outer slightly curved members connected by a shorter inner member, the outer members having at their ends ball shaped projections, one of said outer members being provided with a tongue extending in the direction of the other outer member and slightly projecting beyond the latter outer member, substantially as described.

45 4. A fastening for dress apparel, consisting of an S-shaped double spring clip having two outer slightly curved members connected by a shorter common inner member, and a tongue integral with one of the outer mem-

bers, said tongue extending in the direction of the other outer member and being provided with an eye.

Signed at Berlin, Germany, this 16th day of September, 1929.

ALBERT WICHMANN.
